SYLVESTER E. STAGGS, OF NEW YORK, N. Y., ASSIGNOR OF ONE-HALF TO
EMMY STAGGS, OF NEW YORK, N. Y.

ARTIFICIAL LIMB.

SPECIFICATION forming part of Letters Patent No. 772,753, dated October 18, 1904.

Application filed December 8, 1903. Serial No. 184,281. (No model.)

To all whom it may concern:

Be it known that I, SYLVESTER E. STAGGS, a citizen of the United States, and a resident of the city of New York, borough of Manhattan, in the county and State of New York, have invented new and useful Improvements in Artificial Limbs, of which the following is a full, clear, and exact description.

This invention relates to certain novel and useful improvements in artificial limbs.

In the present instance I have in contemplation as the main object of the invention the provision of an improved artificial upper leg member, a knee-joint, a lower leg member, an ankle-joint, and a foot member, these parts all being designed to be correlated and arranged as is hereinafter specifically recited.

Another object of my invention is the provision of means for adjusting and controlling the tension of the knee-joint in such manner that the latter may be suited to various conditions.

Still a further object is to so construct the ankle connection of the limb that freedom of movement will be at all times secured, while a safe and comfortable joint will be attained.

Finally, I have in view the provision of an artificial limb which will embody the essential and desirable features of simplicity, durability, economy, safety, and convenience.

With the above-recited objects and others of a similar nature in view my invention consists in the construction, combination, and arrangement of parts as is described in this specification, delineated in the accompanying drawings, and set forth in the appended claims.

Reference is to be had to the accompanying drawings, forming a part of this specification, in which similar characters of reference indicate corresponding parts in all the figures.

Figure 1 is a view in side elevation of a limb embodying my improvements. Fig. 2 is a rear view, partly in elevation and partly in section, such view being taken approximately on the line 2-2 of Fig. 1. Fig. 3 is a longitudinal sectional view taken centrally through my improved limb. Fig. 4 is a transverse sectional view taken on the line 4-4 of Fig. 1.

Fig. 5 is a similar view taken on the line 5-5 of Fig. 1. Fig. 6 is a transverse sectional view taken on the line 6-6 of Fig. 1 and looking in the direction of the arrows. Fig. 7 is a longitudinal sectional view of a slightly-modified form of upper leg portion, and Fig. 8 shows an upper leg portion having an air-valve.

For the purpose of convenience in description my improved limb may be considered as comprising a foot member A, an ankle connection B, secured to the foot, a lower leg portion C, jointed to the ankle, and an upper leg member D, connected to the lower leg by an improved knee construction.

The foot member of the device (see Fig. 3) consists, essentially, of a wooden block 5, somewhat oblong in shape and formed with a pointed toe portion 6, said block having a covering of rawhide 7 secured thereto in any desired manner. Over the covering of rawhide and surrounding the same is a layer of felt 8, the felt projecting, as at 9, to form the body of the toe portion of the foot, such felt in turn being covered with a layer of fabric 9^a, formed of canvas and rubber, the latter then being incased in calfskin or the like 10, such calfskin forming the outer surface of the foot, while for the purpose of giving resiliency and spring to the toe I insert a spring 11, of whalebone or other suitable material, between the fabric and the outer calfskin covering.

In the wooden-block portion of the foot member I form a horizontal groove or channel 12, designed for the purpose hereinafter described, and from such grooved portion down through the wooden block extends a vertical bore 13, terminating in a relatively widened portion 14. The wooden-block member is also provided with a cavity 15, formed in the heel portion thereof, and a similar cavity 16 is formed at the front thereof, such cavity being designed to form a seat or bed for the cushion of the ankle portion.

The upper surface of the foot portion is cut away, so as to form a shoulder 17, such cut-away portion of the shoe acting as a bed for the ankle member B. This ankle member is of a peculiar construction comprising, as it does, a body portion formed of any suitable

light material, such as aluminium or the like, and comprises, essentially, an upper portion 18 and a lower relatively widened instep portion 19. The under surface of the aluminium 5 ankle portion is preferably convex and is formed with a transversely-extending bearing 20, (see Fig. 6,) said bearing being formed of a brass tubular portion 21, cast integral with the aluminium of the ankle portion, this 10 journal having lugs or ribs 22 formed thereon. The central portion of the journal is cut away, so that such journal is really formed of two transverse tubular sections, and through the journal extends a shaft 23, formed of a suitable 15 hard metal, this shaft or bolt 23 being designed to stand the tremendous strain which must necessarily be placed upon the same in walking.

Secured to the shaft 23, at the central portion thereof, and extending down through the space between the two sections of the journal is a metal bolt 24, said bolt being connected with the shaft through the medium of an eye portion 25, the shank of such bolt passing 20 through the vertical bore 13 of the foot portion and being secured in the widened portion 14 of the bore through the medium of any suitable nut 26, a washer 27 being also provided. From this construction it will be 25 noted that the single integral ankle member will be firmly and safely secured to the foot member, and in order to cushion the rocking motion of the ankle upon the foot and render the limb comfortable I have provided a rear 30 or heel cushion 28, formed of some suitable resilient material—such as rubber, a steel spring covered with leather, or other material—the lower end of said cushion fitting in the cavity 15 of the foot portion, while the 35 upper end thereof is designed to seat in a brass socket 29, cast in the rear of the ankle portion B. In the front cavity 16 of the foot member is also seated a rubber cushion 30, which is designed to relieve the pressure 40 placed upon the forward part of the foot and to secure comfort to the wearer of the limb.

The upper portion 18 of the ankle B is of slightly-reduced diameter in cross-section, a shoulder, as at 31, being formed circumferentially of the member at the juncture of the 45 portion 18 with the instep portion 19, and this construction will be found extremely useful, as the reduced portion is designed to be inserted within the lower leg member C. 50 This lower leg portion is formed mainly of rawhide, and at the point where it is connected with the ankle member the rawhide is designed to fit over the reduced portion of the ankle and abut against the shoulder 31.

60 In order to connect the lower leg with the ankle portion, copper rivets or other fastening means may be employed, these latter being arranged in a row circumferentially of and extending through the leg member C and 65 the ankle portion, the heads of such rivets

being upset in the ordinary way. Extending longitudinally of the lower leg portion are strengthening strips or bars of metal, such as steel or the like, (shown at 32, see Figs. 2 and 5,) each of such bars lying along the side portions of the lower leg and connected to the ankle portion by certain of the rivets heretofore mentioned, the upper end of each of said metal strips terminating in an eye portion 33, designed to permit the passage of a tubular knee-bolt 34, said bolt connecting the upper leg member with the lower leg member at the knee portion 35. The upper edge of the lower leg portion is strengthened by a metallic band of any suitable character, such as shown at 36, said band being covered or trimmed with any suitable material, such as sole-leather, while the strengthening-strips of the bars 32 32 are also covered with a trimming of sole-leather, as shown at 37, the 75 80 85 90 95 100 105 110 115 120 125 130 135 said trimming being of any design or shape.

The knee portion, as will be seen by reference to the drawings, is formed at the lower extremity of the upper leg portion and is preferably semicircular in contour. The bolt 90 34, which connects the knee with the lower leg, extends through a bearing-sleeve 38, formed of any suitable material, such sleeve having its end portions supported in blocks 39 39, secured at opposite sides of the portion 35. This tubular shaft or bolt 34 is secured through the medium of screw-nuts 40, threaded therein at each end thereof, and for the purpose of permitting the bolt to act as a lubricating device I have formed a groove 100 extending circumferentially of the bolt at 41^a, and a perforation or small hole 41 is made through the grooved portion, such hole permitting any suitable lubricant to pass therethrough and to lubricate the bearing. This 105 construction will be clearly seen by reference to Fig. 4.

In the present construction of limb the ball portion 35 of the knee is also formed of aluminium, and said knee portion is rigidly connected with the upper leg portion B at the lower end of the latter through any suitable means, such as a plurality of copper rivets or the like, the point of juncture of the knee with the leg portion being covered with a band of 110 any suitable material, (shown at 42.) This knee portion is formed with a semicircular slot cut approximately centrally in the ball 115 35 and having its end extending in a vertical direction, said slot being indicated at 43 and being designed for the purpose hereinafter set forth.

It is of course necessary in constructing a suitable limb that there should be some play or movement permitted at the knee portion, and to accomplish this I have adopted the following means: Extending transversely through the lower leg portion is a bar 44, (see Figs. 3 and 5,) which bar is adapted to be connected with a knee-cord 46, the ends of 120 125 130 135

the cord having loops formed thereon and through which the bar passes, such cord passing upward and through a bracket or fastening-clip 47, secured to the back of the upper leg portion directly above the termination of one end of the slot. When the knee is turned so that the upper leg portion is at an angle to the lower leg portion, as is shown in Fig. 3, such cord will also bend, and its free inward movement is permitted by the slot.

In order to tension and to assist in connecting the upper portion of the limb movably with the lower portion, I secure an elastic band near the point of juncture of the ankle with the lower leg, as shown at 49, said band extending longitudinally of the front or shin portion of the leg, and at its upper end is connected at 50 with a flat metallic spring 51, said spring passing through the slotted portion of the knee portion and passing out through an opening 51^a, arranged near the point of juncture of the knee portion with the stump-socket or upper leg portion.

It is often necessary or desirable to tension or regulate the movement of the upper limb-section relative to the lower one, and for this purpose I have provided the spring 51 with a finger-loop 52 and a catch 53, secured adjacent to the finger-loop, said catch being in the nature of a small pin or stud adapted to be brought into alinement and inserted within any desired one of a plurality of openings or apertures 54, formed in a strip 55, which strip is secured longitudinally of the front of the upper leg portion. It will be evident that when it is desired to tension the movement of the sections of the limb it is only necessary to grasp the loop and pull it upward to release the catch from one of the apertures, and then through the elastic cord and spring the desired tension may be obtained, and the catch is then slipped back again into one of the apertures.

The upper leg section or member is in the form of a stump-socket and is constructed of an outer shell 56, formed of rawhide, and an inner shell 57, formed of sole-leather or similar material, the sole-leather overlapping the rawhide at the upper end thereof, so that a band or trimming 58 is formed at the upper portion of the limb. In many instances it is necessary to adjust the limb to suit certain patients, and for this purpose the upper leg-section is formed with a vertical opening, the longitudinal edges of the material adjacent to said opening being provided with a plurality of eyelets, as at 59, designed to receive a lacing-cord 60, the construction being such that the upper section may be tightened or loosened or adjusted slightly to suit the party wearing the limb.

The limb as described may be secured to the stump in any desired manner, such as by straps or the like.

In Fig. 7 of the drawings I have also shown a slightly-modified form of limb. In this

modification the upper leg portion has mounted therein an inner stump-socket 61, which is tensioned in its vertical movement by a spring 62, coiled about a rod 63, one end of which passes through a transverse block 64, while the other end is seated in a small chamber 65, formed in the bottom of the inner socket.

In Fig. 8 the upper leg portion is provided with an air-valve 66, designed to permit the escape of air when the limb is thrust or pushed down into the socket, such valve closing after the air has been expelled, and the limb will adhere firmly to the stump. It will be noted that in Fig. 8 the stump-socket is entirely closed, except at the upper end.

From the above description, taken in connection with the accompanying drawings, the manner of employing my improved limb will be readily apparent. It will be seen that I have provided a simple device and one which will be found exceedingly useful by persons who have had one or both of their lower limbs severed or amputated at a point above the knee, and while I have shown and described a full-sized artificial limb it will of course be understood that the lower portion of such limb—that is to say, the part including the lower leg-section, the ankle-section, and the foot member—may be formed or made to suit parties who have had a limb severed at a point below the knee, in this case the upper leg-section and the knee-joint being omitted.

The use of the rawhide and aluminium forms an extremely strong, light, and durable structure, while the integral ankle portion gives rigidity and strength and at the same time freedom of movement.

The parts of the limb, especially the upper leg-section and the lower leg-section, may be strengthened and formed in any suitable or preferred manner, and it will be further evident that there may be variations and modifications in regard to certain details of construction without departing from the essential features of the invention or sacrificing any of the advantages thereof.

Having thus described my invention, I claim as new and desire to secure by Letters Patent—

1. The combination of an upper leg-section, a lower leg-section, an ankle portion, and a foot member connected to the ankle portion, said foot member comprising a wooden portion, a rawhide covering for the wooden portion, a body of felt secured to the rawhide covering and wooden portion, a coating of canvas fabric for the felt, and a covering of rubber over the canvas, substantially as set forth.

2. The combination of a leg portion, a foot member, an ankle portion connecting the leg portion with the foot member, said ankle portion comprising an integral metallic body having a reduced upper portion connected with the leg and a flared, enlarged lower portion

constituting a bearing, a tubular shell surrounding said bearing and a connecting-bolt in said bearing, through the medium of which the ankle portion is secured to the foot member.

- 5 3. The combination of a leg portion having a transverse groove, a foot member having a bore, an ankle portion connecting the leg portion with the foot member, a hard-metal bearing cast integral with the material of the ankle portion and adapted to lie in the groove formed transversely of the leg portion, a shaft and bolt carried by said hard-metal bearing and designed to extend through the bore formed in the foot member, and a nut designed 10 to thread upon the shank of the bolt, for uniting the foot member with the ankle portion, substantially as set forth.

4. An article of manufacture, comprising a wooden portion, a rawhide covering therefor, 15 a layer of felt over the rawhide, a layer of canvas fabric over the felt, and a covering of vulcanized rubber over the canvas.

5. The combination of a lower leg portion formed of a body of rawhide, leather trim- 20 ming for said rawhide, and a plurality of metal strips or bars extending longitudinally of the leg portion, certain of said bars having eye portions formed thereon, an upper leg portion formed of a body of rawhide, knee portion, 25 designed to be secured to the lower leg portion, and a bolt passing through the aluminium knee portion of the upper limb and designed to be supported by the metallic strips.

6. The combination of an upper leg portion, 30 a lower leg portion, a knee portion carried by the aforesaid upper leg portion, means for pivotally connecting the two leg portions at the knee, a knee-cord connecting the two sections, and means for adjusting the tension or 35 regulating the movement of the two sections relative to each other, said means including a spring and a latching device carried by said spring on the outside of one of the leg portions, designed to engage with the upper leg 40 portion.

7. The combination of an upper leg portion, a lower leg portion, a metallic knee portion carried by the aforesaid upper leg portion, a plurality of metallic strips extending longitudinally of the lower leg portion, a tubular bolt passing through said strips and through 45 the metallic knee portion, for connecting the knee portion to the lower leg portion, a

a cord looped at its central portion and connected to the upper leg portion at the rear of the knee, the free ends of said cord being secured within the lower leg portion, a lacing-cord passing through apertures or eyes formed in the upper leg portion, for adjusting the size of said upper leg portion, means for tensioning the movement of the limb at the knee, such means including a spring and a latching device carried by said spring and designed to engage with notches formed in the upper leg portion, an ankle portion secured to the lower leg portion, and a foot member connected to the ankle portion.

8. An artificial limb comprising a foot portion, a leg portion, and means secured in the leg portion, for permitting the escape of air 70 therefrom when the leg portion is filled, and for preventing the admission of air thereto, the said means being so arranged as to close after the air has been expelled from the leg portion.

9. The combination of an upper leg portion, constructed of an outer rawhide covering and a lining of leather, an aluminium knee portion secured to the upper leg portion, and a lower leg portion pivotally connected to the knee 80 portion, said lower leg portion being formed of rawhide and having strips of strengthening material secured to the rawhide.

10. An artificial limb comprising an upper leg portion, a knee portion rigidly secured to 85 said upper leg portion, a tubular bearing-sleeve mounted transversely of the knee portion, a lower leg portion, and a tubular bolt, provided with an oiling-aperture, an oil-carrying groove passing through the sleeve with 90 in the knee portion, and pivotally securing the lower leg portion to the knee portion.

11. An artificial limb including a tubular leg portion, an inner socket portion movably mounted in the leg portion, and spring-tension means for cushioning the movement of the socket within the upper portion, comprising a rod carrying the spring, a head on the rod, and means for holding said head.

In testimony whereof I have signed my name 100 to this specification in the presence of two subscribing witnesses.
